BUCKLE

Alfred Johnson, Chicago, Ill.

Application September 23, 1938, Serial No. 231,380

8 Claims. (Cl. 36—71)

This invention relates to a buckle, and more particularly to a buckle for holding a strap in tightened or adjusted position.

The primary object of the invention is to provide a new and improved buckle which will positively hold a strap in tightened or adjusted position, which permits quick and instant release of the strap when opened, allowing the strap to slip quickly and easily when the buckle is unsnapped or released, and which is provided with new and improved means for permitting the buckle to be readily fastened in position.

Another object of the invention is to provide a buckle adapted for numerous purposes, but particularly adaptable for fastening to a shoe, whereby a strap on the shoe passes through an opening or eyelet in the buckle, the buckle co-operating and receiving therethrough an eyelet, which consists in securing the buckle to the member to which it is applied, there being spring means for urging the locking end of the buckle in a predetermined position, said buckle also being provided with an attaching member to permit the buckle to be securely fastened to the member or strap with which it co-operates.

A further object of the invention is to provide a buckle which will securely lock a member such as a strap in adjusted position, which will permit the strap or other member to be fastened to slip easily and quickly through the buckle when released, which is rigid and durable in construction, and which can be readily and economically manufactured, the main parts of the buckle being stamped from sheet material.

Numerous other objects and advantages will be apparent throughout the progress of the following specification.

The accompanying drawing illustrates a selected embodiment of the invention and the views therein are as follows:

Fig. 1 is a detail perspective view of an article of footwear and embodying the invention, the shoe having a cradle or leather loop arranged in the bottom of the shoe to support the arch of the wearer, the cradle or loop having an extending strap which extends through an opening in the shoe and adapted for engagement with the buckle;

Fig. 2 is a detail transverse sectional view through an ice skate shoe of the type disclosed in Fig. 1 and embodying the invention;

Fig. 3 is a top plan view of the improved buckle showing the same applied to a member such as a shoe;

Fig. 4 is a detail transverse sectional view on the line 4—4 of Fig. 3;

Fig. 5 is a detail longitudinal sectional view on the line 5—5 of Fig. 3;

Fig. 6 is a detail top plan view of the bottom 5 or lower part of the buckle; and

Fig. 7 is a detail sectional view showing the eyelet as an integral part of the buckle.

The particular buckle herein shown for the purpose of illustrating the invention comprises a 10 two-part buckle member 8 having a lower or bottom element or part 9 and a co-operating upper or top element 10. The bottom element 9, Figs. 3-6, is relatively flat but slightly curved when applied to a shoe to conform with the outer 15 contour of the shoe, and has an upper enlarged projecting end 11, Fig. 6, provided with a hole 12 therethrough. A fastening member, such as a strap 13, on a shoe 14, Figs. 1, 2, and 3, is adapted to extend and be engaged by the upper 20 part 10 of the buckle to hold the strap in its tightened or adjusted position. The lower end of the inner or lower element 9 is provided with an extension 15, Fig. 6, to provide ears or legs 16 on each side of the central bottom portion 17, the bottom portion 17 being integrally connected to the parts 11 and 15, as clearly shown in Fig. 6. 25

Side ears 18 are integrally formed on the body portion 17 and are bent upwardly and outwardly, as clearly shown in Fig. 4, to provide pivot supports or trunnions 19. These trunnions are adapted to have pivotal engagement with the upper or outer part 10 of the buckle and hold the two parts in assembled relationship. The inner or bottom part 9 is also provided with a pair of 30 slits 20, Fig. 6, providing a strip 21 raised from the surface of the body 17 a slight amount and receiving one end 22 of a spring member 23. The spring member 23 co-operates with the upper portion 10 of the buckle to urge the part 10 35 in a predetermined position with respect to the part 9.

The part 9 is attached to the member for which the buckle is designed, and this member may constitute a shoe 14 or it may constitute a 40 strap or any other co-operating structure. If the buckle is to be applied to a shoe the part 10 is arranged in position with the opening 12 in the element 9 co-operating with a slit or opening 24 formed in the side of the shoe 14. The bottom 45 element 9 is then fastened to the side of the shoe by attaching means, such as rivets 25, passing over the extending legs or arms 16 and clinched inside of the shoe. To hold the lower part 9 in 50 fixed position relative to the shoe, an eyelet 26, 55

Fig. 5, is arranged in the opening 12 in the member 9 and extends through the opening 24 with the upper portion 21 of the eyelet engaging the upper portion of the part 11 surrounding the opening 12. The inner edge of the eyelet 26 is then clinched over, as indicated at 28, Fig. 5, to fasten securely the eyelet to the shoe and at the same time securely locking the member 9 in place.

10 The upper part 10 of the buckle is also made from a single piece of material and is slightly curved, as clearly shown in Fig. 5. The part 10 is provided with integral inwardly or down-turned ears 29 which are provided with openings

15 30 to receive the pivotal bearings or trunnions 19 on the ears 18 of element 9. The top 10, therefore, is pivotally connected to the bottom element 9.

20 The spring 23 extends diagonally between the parts 9 and 10, as clearly shown in Fig. 5, and has its upper end 31 soldered or otherwise fixed to the under surface of the member 10 whereby the spring 23 urges the outer end of the member 10 away from the element 9, bringing the locking end 32 of the upper part 10 downwardly toward the element 9. The locking end 32 is provided with a plurality of teeth 33 which are adapted to engage and bite into the strap or other fastening member 13. The rear end of the member 10 is bent upwardly, as indicated at 34, Fig. 5, and is provided with an opening 35 therethrough through which the end of the strap may be received, as clearly shown in Fig. 5.

25 The buckle 8, of course, may be used for straps, belts, and other purposes but is shown as being applied to a shoe. It has been found in actual practice that it is particularly applicable to a shoe or other article of footwear, and more particularly to athletic shoes such as skate shoes.

30 In the embodiment shown, the athletic shoes shown in Figs. 1 and 2 are provided with a loop or cradle to support the arch. The cradle or support member 36 of which the strap 13 is a part supports the cuneiform bones of the arch, and 35 due to the rearward pull also relieves the strain on the metatarsals, the strap or member 36 being of a width substantially to embrace the cuneiform bones. The member 36 is adapted to extend across the bottom of the shoe and 40 then up over the shoe across the top of the arch of the foot and over the instep and then downwardly on one side thereof where the strap 13 is adapted to extend through the notch or opening 24, and be engaged by the buckle 8. 45 Pulling on the strap 13, therefore, causes the member 36 snugly to engage the arch of the wearer and provide the proper support.

50 The buckle is constructed and arranged to co-operate with the member 36 by receiving the strap 13 and locking the strap 13 by the teeth 33 engaging the strap as it extends from the inside of the shoe through the opening 24. Any inward pull on the member 36 or the strap end 55 13 will merely tend to pull the locking end 32 of the buckle and imbed the teeth 33 deeper into the material from which the strap 13 is made. The strap 13 is, therefore, held rigidly in tightened or adjusted position and can not move by 60 slipping. However, when it is desired to release the strap, pressure is applied to the end 34 of the buckle, raising the end 32 and enlarging the opening 24 which is restricted in size because the end 32 of the buckle, extends over 65 the opening and impinges the strap between the

locking end 32 and the sides of the material or eyelet surrounding the opening 24.

In Fig. 7 there is shown a slight modification of the buckle wherein the member 9 about the opening 12 thereof is provided with an integral 5 eyelet 40. The integral eyelet 40 reinforces the material about the opening 24 in exactly the same manner in which the eyelet 26 does.

After the strap is tightened to the adjusted position and held in locked engagement by the 10 locking end 32, the free end of the strap may be inserted through the opening 35 in the end or tail piece 34.

15 While the invention is particularly adaptable for use on footwear, such as athletic shoes, the 10 buckle is also adapted for securing any kind of belt or strap, and is particularly adaptable for use on straps attached to life belts in airplanes because the strap is tightly locked in place and can not slip but can be instantly released by a 20 downward pressure on the tail piece 34. For use with life belts it is desirable and expedient that the end of the strap be not laced through the opening 35, as it is preferable and advantageous that the life belt be released immediately upon pressure without the necessity of first pulling the free end of the strap through the eyelet 35.

25 The buckle is stamped from sheet metal and can be readily and economically manufactured. 30 The buckle in assembled position is neat, is provided with means for securing fastening it to a member or structure, and is ornamental in appearance as well.

35 The invention further contemplates the provision of reinforcing means about the opening 24, such as the eyelet 26. However, instead of using the eyelet 26 to reinforce the material surrounding the opening 24, other reinforcing means, such as stitching, leather staples, etc., 40 may be employed. However, the use of the metal eyelet 26 is preferred because this eyelet can be employed not only to provide a smooth opening through which the strap passes, but is also used to fasten the buckle to the shoe. 45

50 Changes may be made in the form, construction, and arrangement of the parts without departing from the spirit of the invention or sacrificing any of its advantages, and the right is hereby reserved to make all such changes as 55 fairly fall within the scope of the following claims.

55 The invention is hereby claimed as follows:

1. In combination with a skating shoe having an opening in the wall thereof through which a 60 fastening strap passes, a buckle having an opening adapted to align with said shoe opening, eyelet means passing through said opening for receiving said strap and joining said buckle to the shoe, and a locking member on the buckle adjacent the opening and having a locking edge yieldably urged into juxtaposition with said eyelet for impinging the free end of the strap passing through the eyelet.

65 2. In combination with a skating shoe or the like having an opening therein through which a fastening strap is adapted to extend, said buckle comprising an inner member and an outer member pivotally connected together, openings in opposite ends of said members, the opening in said 7 inner member substantially coinciding with the said shoe opening, and an eyelet arranged in the opening of said inner member and extending through the opening in said shoe and engaging said openings for fastening the buckle upon the 7

shoe while permitting free passage of the end of the strap, said outer member having a locking edge adjacent said opening carrying the eyelet for impinging the strap extending therethrough, the opening in the outer member being adapted to receive the end of the strap.

5. In combination with a skating shoe having an opening in the wall thereof through which a fastening strap passes, a buckle having an opening adapted to align with said shoe opening, eyelet means passing through said opening for receiving said strap and having its opposite extremities formed over for joining said buckle to the shoe, a locking member pivotal on said buckle and having a locking edge adapted to impinge the free end of the strap extending through said eyelet means and frictionally engaging said strap in cooperation with said eyelet for interlocking with the strap, and spring means urging said

20 locking member into strap impinging position.

4. In combination with a skating shoe having a strap adapted to pass over the instep of the foot and an opening in the ball of said shoe for receiving the end of said strap, a buckle on said shoe, said buckle comprising an inner member and an outer member pivotally connected together, an opening in said inner member coinciding with said shoe opening, and an eyelet arranged in the opening of said inner member and extending through the opening in the shoe for accommodating the end of the strap while securing the inner member fixedly to the shoe, said outer member having a strap-engaging locking edge pivotal to locking juxtaposition adjacent said eyelet means and being adapted to coact therewith for impinging the strap in locking engagement.

5. In an article of the class described comprising a flexible wall of relatively large extent and a strap on the inner side of said wall adapted to extend through said wall and to be interlocked therewith adjacent the outer side of said wall, said wall having an aperture formed therein to removably accommodate the strap, a plate member having a cooperative aperture disposed adjacent the outer surface of said wall with its aperture in congruent alignment with said first-named aperture, eyelet means projecting through said aligned apertures to receive said strap and having formed over portions oppositely engaging said plate and wall for permanently joining said elements together, and a clamping member on said plate and having a clamping edge urged into clamping juxtaposition with a side of said eyelet to lockingly engage a strap passing therethrough.

6. In an article of the class described comprising a flexible wall of relatively large extent and a strap on the inner side of said wall adapted to extend through said wall and to be interlocked therewith adjacent the outer side of said wall, said wall having an aperture formed therein to removably accommodate the strap, a plate member having a cooperative aperture disposed in

flatwise relationship adjacent the outer surface of said wall with its aperture in congruent alignment with said first-named aperture, eyelet means projecting through said aligned apertures to receive said strap and having formed over portions oppositely engaging said plate and wall for permanently joining said elements together, and a clamping member on said plate and having a clamping edge urged into clamping juxtaposition with a side of said eyelet to lockingly engage a strap passing therethrough, said plate having a portion extending to a position relatively remote from said eyelet fastening means, and lateral, marginal projections extending from said plate and fastened permanently to the said wall.

7. In an article of the class described comprising a flexible wall of relatively large extent and a strap on the inner side of said wall adapted to extend through said wall and to be interlocked therewith adjacent the outer side of said wall, said wall having an aperture formed therein to removably accommodate the strap, a plate member having a cooperative aperture disposed adjacent the outer surface of said wall with its aperture in congruent alignment with said first-named aperture, eyelet means projecting through said aligned apertures to receive said strap and having formed over portions oppositely engaging said plate and wall for permanently joining said elements together, and a clamping member on said plate and having a clamping edge urged into clamping juxtaposition with a side of said eyelet to lockingly engage a strap passing therethrough, said clamping member being yieldably pivoted about pivot means located at a point relatively remote from said locking side of the eyelet.

8. In an article of the class described comprising a flexible wall of relatively large extent and a strap on the inner side of said wall adapted to extend through said wall and to be interlocked therewith adjacent the outer side of said wall, said wall having an aperture formed therein to removably accommodate the strap, a plate member having a cooperative aperture, disposed adjacent the outer surface of said wall with its aperture in congruent alignment with said first-named aperture, eyelet means projecting through said aligned apertures to receive said strap and having formed over portions oppositely engaging said plate and wall for permanently joining said elements together, and a clamping member on said plate and having a clamping edge urged into clamping juxtaposition with a side of said eyelet to lockingly engage a strap passing therethrough, said clamping means comprising a member pivoted upon said plate at a point substantially removed from said eyelet, said member having a portion extending beyond said pivot, and compression spring means between said last-named portion and the plate for urging the clamping edge into locking engagement with the eyelet at all times.

ALFRED JOHNSON.
